BONE CUTTING SAW OR SIMILAR ARTICLE

Filed Dec. 5, 1945

FIG. 1.

FIG. 2.

INVENTOR :
DANIEL DOHM JR
BY *Ed Hoffman*
ATTORNEY

UNITED STATES PATENT OFFICE

146,737

DESIGN FOR A BONE CUTTING SAW OR
SIMILAR ARTICLE

Daniel Dohm, Jr., St. Louis, Mo., assignor to
Dohm & Nelke, Inc., St. Louis, Mo., a corpora-
tion of Missouri

Application December 5, 1945, Serial No. 124,394

Term of patent 14 years

(Cl. D93—4)

To all whom it may concern:

Be it known that I, Daniel Dohm, Jr., a citizen of the United States of America, residing at the city of St. Louis, State of Missouri, have invented a new, original, and ornamental Design for a Bone Cutting Saw or Similar Article, of which the following is a specification, reference being had to the accompanying drawing, forming a part thereof.

In the drawing Figure 1 is a perspective view of a bone cutting saw or similar article of my new design, and Figure 2 is a top plan view of the bone cutting saw or similar article shown in Figure 1.

I claim:

The ornamental design for a bone cutting saw or similar article, as shown.

DANIEL DOHM, JR.
